ATTORNEY'S.

UNITED STATES PATENT OFFICE.

GEORGE H. ALLEN, OF CLINTON, NEW YORK.

DESIGN FOR A MATCH-SAFE.

SPECIFICATION forming part of Design No. 26,295, dated November 17, 1896.

Application filed July 10, 1896. Serial No. 598,767. Term of patent 3¹ years.

To all whom it may concern:

Be it known that I, GEORGE H. ALLEN, a citizen of the United States, residing at Clinton, in the county of Oneida and State of New York, have invented and produced a new and original Design for Match-Safes, of which the following is a specification, reference being had to the accompanying drawing, showing the same.

10 The figure of the drawing shows my match-safe in perspective view.

The leading features of my design are the rectangular block shape of the body of the

safe provided with two cup-like openings or pockets in the upper surface with the edges 15 of receptacles in the pockets projecting slightly above the upper surface of the body.

What I claim is—

15 The design of a match-safe as herein shown and described.

In witness whereof I have affixed my signature in presence of two witnesses.

GEORGE H. ALLEN.
